UNITED STATES PATENT OFFICE.

MAX ELLRICH, OF JERSEY CITY, NEW JERSEY, ASSIGNOR, BY MESNE ASSIGNMENTS,
TO MARIE CHRISTENSEN, OF BROOKLYN, NEW YORK.

CORK-PACKING MACHINE.

Application filed January 21, 1921. Serial No. 438,907.

To all whom it may concern:

Be it known that MAX ELLRICH, citizen of the German Republic, residing at Jersey City, in the county of Hudson and State of New Jersey, have invented certain new and useful Improvements in Cork-Pack ing Machines, of which the following is a specification.

The present invention relates to a machine for filling and packing tubes or molds with ground or comminuted material, such as cork to produce sticks or rods, from which subsequently disks are cut to be used with crown caps.

The cork disks may consist of natural cork or so called composition cork. Natural cork, even of the best quality, is porous. The use of composition cork is steadily increasing owing to the low price as well as its homogeneity.

Composition cork is made of granulated cork refuse mixed with a binder consisting ordinarily of glue, glycerine and certain chemicals having preserving properties.

The cork rods are usually made 1" in diameter and two feet in length. The cork mixture is filled in tubes, compressed to $\frac{1}{4}$ of its original volume, baked in an oven and cooled. The mixture of cork and binder must be handled with care. The sticky binder partly is absorbed by the cork and partly forms a coating around the cork granules. By the cooling and drying process the coating or skin loses its stickiness.

As long as the cork is not heated nor squeezed it can be easily treated as it easily flows by its own gravity into the tube to be filled. But if the cork is heated or squeezed the outer skin melts or is severed and the sticky substance appears on the outer surface forming a sticky mass which no longer can be treated. Therefore, the cork packing devices must be so constructed as to reduce squeezing to a minimum and avoid frictional contact with heated parts of the machine.

Likewise the compression of the cork mixture to $\frac{1}{4}$ of its original volume requires special attention.

In a substance like cork the compression pressure is not readily transmitted. If, for instance, we fill an eight foot tube with cork and attempt to compress the cork volume to 2 feet, a cork rod is formed, the upper layer of which becomes steel hard, while the lower layer retains its original consistency. Ex-

perience has shown that uniform compression is attained by first filling the tubes with a charge of 5" to 6" and compressing said charge to about 1 $\frac{1}{3}$ ", then adding a new charge of same volume and compressing this charge to the same degree, so that the tube now will have 2 $\frac{2}{3}$ " compressed cork, and so on, until the tube is completely filled.

From the foregoing it follows that the depth to which the compression plungers enter the tubes must become smaller with each stroke, until at the last stroke it only touches the edge of the tube.

Since the exact size of each charge or the degree of compression depends on one hand upon the quality of the cork to be treated and on the other upon the temperature and humidity of the air, the charge feeding device must be adjustable.

With the hitherto used cork packing machines the heavy plungers working in the tubes are alternately lifted to a certain height and dropped. Since the stroke and weight are constant the power with which the plungers act upon the cork theoretically remains the same. In practice, however, variable resistances due to friction render the thrusts non-uniform.

Nor do these machines take any account of the variable resistances offered by different qualities of cork mixture to the compression and changed weather conditions. As a consequence, the rods produced by such machines are of non-uniform density.

With my invention these drawbacks are entirely obviated.

In the accompanying drawing in which similar reference characters denote corresponding parts, Fig. 1 is a front elevation of my machine; Fig. 2 is a side elevation thereof; Fig. 3 is a top plan view of the machine; Fig. 4 is a vertical section on line 4—4 of Fig. 1; Fig. 5 is a top plan view of the driving mechanism arranged below the table; Fig. 6 is a section on line 6—6 of Fig. 5; Fig. 7 is an enlarged section on line 7—7 of Fig. 1 showing the compressor in one position; Fig. 8 is a similar section to Fig. 7 showing the compressor in a different position; Fig. 9 is an enlarged section on line 9—9 of Fig. 1; Fig. 10 is a front view of the large cam; Fig. 11 is a section on line 11—11 of Fig. 4; Fig. 12 is a section on line 12—12 of Fig. 4; Fig. 13 is a section on line 13—13 of Fig. 4; Fig. 14 is an end ele-

2
vation of a modification showing a tube unit construction, and Fig. 15 is a side elevation thereof.

Referring to the drawings in detail 10
5 denotes a frame comprising a substantially
rectangular base plate or table 10'. Projecting vertically from and fixed to the front
part of the table or base plate 10' are two
posts 11, which are connected together by
10 two cross bars 12 and 13, the cross bar 12
being arranged near the center of the posts
and the cross bar 13 near the upper ends
thereof (Figs. 1 and 2).

Revolvably mounted in the table 10' is a
15 vertically extending spindle 14 on which is
fixed a turntable composed of two super-
posed supports 15, 16, the lower support 15
being arranged near the table 10' and the
upper support 16 near the bottom of the
20 cross bar 12. These supports serve to carry
two rows of vertically extending chambers,
molds or tubes T to be packed by the apparatus
forming the subject of this invention.
The lower support 15 is in form of a solid
25 plate on which the tubes T rest with their
open lower ends and the upper one 16 is per-
forated as 16' to removably engage the upper
open ends of the tubes. The tubes to be
filled are at the rear sides of the supports
30 15, 16 while the empty tubes rest on the front
sides thereof (Figs. 3 and 4).

The cross bar 12 is provided with a plu-
rality of tubular openings 12' which are of
exactly the same diameter as the inner di-
35 ameter of the tubes and which are spaced
apart to conform with the spacing of the
tubes so as to be in alinement with the latter
(Fig. 4).

Projecting forwardly from the main cross
40 bar 12 is a bracket 17 in which is revolvably
borne the upper end of the vertical spindle
14 carrying the supports 15, 16 of the tubes
T (Figs. 3 and 4).

Extending transversely over the table 10'
45 parallel to and between the cross bars 12,
13 is a beam 18 which is formed at its ends
with sleeves 19 slidably bearing on the posts
11. Fixed to and projecting downwardly
50 from said beam are a plurality of vertical
plungers 20 which are adapted to snugly fit
in the tubes T. There are as many plungers
as there are tubes in a row and the same are
arranged to be in alinement with the rear
55 row of tubes T to be packed. The beam 18
is adapted to receive intermittent vertical re-
ciprocating motion and during each suc-
cessive downward stroke the plungers 20 are
adapted to pass through the openings 12' of
60 the cross bar 12 and enter the rear row of the
tubes T to compress the charge of cork mix-
ture which, while the plungers are in their
raised position flows into the tubes from an
automatically controlled hopper 21 as will
be hereinafter described.

65 According to hitherto used systems the

tubes are packed by plungers of successively
reduced lengths, and must be, after each
stroke, shifted into register with another
plunger. This system, known as the Step-
70 rod system, has been found disadvantageous.
First, the continuous change of position of
the tubes entails considerable loss of time,
decreasing the capacity of the machine.
Then, this change of position requires re-
peated centering of the tubes. As the tubes,
75 by wear, lose their perfect roundness, their
exact centering becomes very difficult and
often almost impossible, so that the plungers
when descending are liable not to enter the
tubes, but strike against the edges thereof
80 causing damage to the tubes or to the ma-
chine.

Furthermore, with each change of position
of the tubes a small quantity of cork mixture
is wasted, and since for the standard size of
85 tubes the latter change their position about
twenty times during a complete packing
action, a considerable quantity of material is
wasted.

In addition to these drawbacks, there is
the one entailed by the irregularities in the
filling of the tubes. In the hitherto known
machines, the feeding of the material is ef-
fected through telescoping horizontally mov-
able tubes which alternately register with
90 the hopper and the molds or chambers to be
filled. The material is thus supplied to the
molds through comparatively small open-
ings. During the cool weather the feeding
may be quite regular, but during warm
100 weather the cork becomes sticky and does not
freely flow through these openings or tubes.
In hot weather the feeding completely fails
and the operation of the machine must cease.

According to my invention the tubes dur-
ing the entire packing process are retained
in their position. Each downward stroke of
the plunger is carried out in two successive
steps. First, the plungers are allowed to en-
ter the tubes until they become lodged on the
110 loose charge previously fed into the tubes.
Then, the plungers receive an additional pos-
itive movement to compress the charge to
the desired density. While the second step
115 or stroke will be constantly the same, that is,
for instance, for a charge of say 5" column,
about 4½", the first step or first part of the
stroke of the plungers will vary with each
new charge, the same becoming successively
shorter as the charges pile up. The feeding
120 of the charge is effected from the hopper 21
having a large slot like discharge or mouth
21' horizontally extending over the entire
rear set of tubes T and leading into a sta-
tionary measuring chamber 22 hereinafter to
be described, from which a predetermined
charge will be freely and regularly supplied
125 to the molds, chambers or tubes T under all
weather conditions.

The first part of the stroke of the plunger 130

beam 18 is effected by the following mechanism.

Rotatively supported below the table 10' and extending transversely thereto is a horizontal shaft 23 to the ends of which are fixed double armed balance beams 24 carrying at their rear ends weights 25 and which with their forward ends are pivotally connected through the medium of rods 26 with the sleeves 19 of the vertically slidable cross beam 18 (Figs. 1, 2, 5 and 6). The cross beam 18 is perfectly counterbalanced by the weights 25 so that a slight force will be sufficient to move the plungers downwardly to carry out the first part of the stroke in the course of the packing process. This force, however, must be resilient, since the length of the stroke varies with each additional charge. Springs or friction could be utilized for this purpose. I prefer, however, to employ pneumatic means as it is most satisfactory. To this end I provide a suitable double cylinder pump 27 the piston rods 28 of which are connected by means of a crank lever 29 to the shaft 23 so that by the operation of the piston of one or the other cylinder the shaft 23 will be turned in a certain direction and move the plunger beam 18 downwardly or upwardly as the case may be. The balancing beams 24 are adapted to receive just enough power to, on one hand, depress the plunger beam 18 until the plungers are thrust against the loose charge in the tubes or molds T without materially compressing the same, and on the other hand to raise the plungers to their initial inoperative position. The actual compression of the charge is effected during the second step of the downward stroke through the medium of a special positively actuated mechanism which in the following I shall call the "compressor."

In lateral extensions 12², 13' of the cross beams 12, 13 is supported at each end a vertically movable, but not rotary, rod 30. At a lower point above the cross bar 12 this rod 30 is provided with a collar 31 and on its upper end is fixed a centering sleeve 30' (Fig. 1). Rotatively mounted around the rod 30 is a cylinder or hollow body 32 which is centered and held against vertical displacement at its upper end by the sleeve 30' and which rests at its lower end on the collar 31 preferably by means of a ball bearing 33. The lower end of said cylinder 32 is formed integrally with or has attached to it an elongated toothed wheel 34. The upper end of said cylinder 32 carries two superposed ratchets 35, 36 of which the upper one 36 in length is about equal to the stroke of the cylinder 32 while the lower one 35 in length is very short. These ratchets have equal numbers of teeth, say four, as shown in Fig. 9, and the teeth of the two ratchets are arranged at an angle

of 45° relative to one another. Projecting downwardly from the upper cross bar 13 is a rigid arm 37 which at its free lower end is formed with a rigid tooth or dog 38 adapted to alternately engage the said two ratchets 35, 36 to control the rotary motion imparted to the cylinder 32 through a spring mechanism to be hereinafter described (Figs. 1 and 9).

The cylinder 32 on its circumference is provided with a plurality of lugs or fingers 39 which project therefrom and which are arranged in a spiral manner at a certain height from each other. This height between each two adjacent lugs correspond to the extent to which each successive charge is to be compressed during the second step of a compression stroke. In the present example in which the successive charges of about 5" column are adapted to be compressed to 1 1/3" column the distance between the different lugs in height or the vertical stroke of the cylinder 32 is accordingly about 1 1/3".

Meshing with the elongated toothed wheel 34 of the cylinder 32 is a comparatively narrow wheel 40 which is carried by the upper end of a hollow shaft 41 rotatively borne in a bearing 12² projecting upwardly from the extension 12² of the cross bar 12. This hollow shaft 41 is mounted on a solid spindle 42 projecting downwardly through the cross bar 12. The lower end of the hollow shaft 41 has a collar 43 to which is fixed one end of a spiral 44 wound around the lower part of the solid spindle 42 and the other end of which is fixed to said spindle at 45 (Figs. 1 and 2). The lower end of said solid spindle is rotatively supported in a bearing 48 provided on the table 10' and carries a worm gear 46. This gear 46 meshes with a worm spindle 47 rotatively supported in bearings 48^a. The worm spindle 47 is driven through sprocket wheels 50, 51 and chain 52 or the like from a horizontal cam shaft 53 extending transversely over the table 10' and supported in bearings 54 (Figs. 1, 2 and 3).

To completely pack a tube with the cork mixture a number of compression strokes are required. Thus to pack a tube of the standard length of 24" by successive charges of a 5" column and compressing each charge to 1 1/3" eighteen compression strokes of the plungers 20 are required. All the time during a complete packing operation the molds or chambers T are held stationary. At the end of each complete packing operation and before a new operation commences, the molds or chambers T of the rear set which have been packed are caused to turn away from the packing position, while the front set of empty molds T are brought into the packing position.

The lugs or fingers 39 on the compressor

32 may be advantageously arranged in groups or sets, so that those of each group project in the same direction, and the lugs of the different groups are arranged at an angle to one another. Thus according to the example chosen, there are four groups, with five lugs in each of two groups, and four lugs in each of the remaining groups, the lugs of the different groups being arranged 10 at 90° relative to one another. Only one lug of each group is adapted at a time to engage the vertically movable plunger beam 18, to execute the second part of the compression stroke. The lower end of each rod 15 30 carrying a compressor cylinder 32, is pivotally connected through links 55 to a horizontal arm 56. The latter is fulcrumed to the frame below the table at 57 and carries at its free end a roller 58 adapted to be 20 held constantly in contact with a cam 59 by a spring 60 fastened at one end to the horizontal arm at 61 and the other end to the frame or table 10' at 61' (Fig. 2). The two cams 59 are fixed to the ends of a constantly 25 driven horizontal shaft 62 at the front of and below the table 10' which I shall call the "compressor shaft." The cams 59 when actuating the arms 56 will draw the rods 30 and consequently the compressors 32 downwardly positively effecting thereby a compression stroke of the plungers 20 while the return upward movement of the compressors 32 will be effected through the action of the springs 60 (Figs. 1 and 2).

35 The beam 18, or more exactly each of its sleeves, is provided with a catch 18' which projects toward the respective compressor 32 and is adapted to be engaged by the lugs 39 thereof. Normally the compressor by the 40 action of the springs 60 is held in raised position and its lugs 39 are so positioned as to clear the path of the catches 18' (Fig. 8). This displaced position of the lugs is insured by the engagement of the dog 38 with the short ratchet wheel 35 of the compressor. Just as soon as the compressor commences 45 to move downwardly the dog 38 passes onto the elongated ratchet 36. Owing to the teeth of the ratchet 36 being set at 45° relative to those of the short ratchet 35, the dog 38 will release the compressor 32 for just an instant, permitting it to turn about 45° under the action of the spring actuated pinion 40 meshing with the toothed portion 50 34 of the cylinder 32 thereby bringing a group of grippers of each compressor into the path of the respective catch 18' of the plunger beam 18, i. e., into the position shown in Fig. 7. The lugs on engaging said 55 catches will as the downward movement of the compression continues, transmit motion to the beam 18 causing the plungers 20 thereof to move in the molds or tubes T and compress the charge therein. After the completion of their compression stroke, and be-

fore the beam 18 is permitted to assume its return stroke through the action of the pump 27 the compressor 32 under the action of spring 60 will be lifted into its initial position, thereby bringing the dog 38 back 70 onto the small ratchet 35. In consequence thereof the compressor 32 will be allowed to make a new turn of 45° in which the lugs 39 will disappear from the path of the beam 18 or its catches 18' adopting the position 75 shown in Fig. 8. Therefore, the beam 18 will be allowed to rise to its initial position under the action of the pump 27.

During the next downward stroke after a new charge has been fed into the molds T 80 the beam 18 through the action of the pump 27 will again descend until its plungers 20 are thrust against the new charge. This time the lowest position of the beam will be 1 $\frac{1}{3}$ " less than at the preceding stroke. The 85 compressor 32 thereupon will be moved down to the same extent as before. At the outset of this movement the dog 38 passing from small ratchet 35 onto the long ratchet 36 will permit the compressor 32 to make 90 a turn of 45° bringing the next group of lugs 39 into the path of the catches 18' of the plunger beam 18 and force the latter down to the same extent as before, that is 95 $4\frac{1}{2}$ " as per present example. This is repeated 100 eighteen times. Owing to the grouping of the lugs 39 the compressor has to make a full rotation during each four compression strokes. The springs 44 actuating the pinions 40 would completely unwind themselves during that period. In order to retain 105 the springs at uniform force during each compression stroke, the spindle 42 must be given a full revolution during the same period. This is accomplished by selecting a 110 ratio of 1:4 in the transmission of rotation of the spindles 42 from the cam shaft 53 through the worm gears 46, 47.

115 The charges are filled from the hopper 21 having an automatically controlled measuring device. The hopper 21 is supported above the table at a suitable elevation from the center cross beam 12 and extends with its mouth 21' over the area occupied by the rear series of molds T to be filled. The measuring device is arranged below the mouth 21' and consists of a box-like structure having a horizontally movable slide 63 at its top acting as a partition between the box and the hopper, and a horizontally slideable bottom or shutter 64. The rear side wall 22' of the measuring box is made adjustable and is fixed to a set screw 65 (Fig. 4) whereby when desired the capacity of the box may be increased or reduced according to the charge desired. The two slides 63, 64, are each connected at the rear to a pair of horizontally movable rods 66 suitably guided in brackets 67, 68 fixed to a stationary part 12' of the cross bar 12. The rods are each 130

actuated by a spring 69 the tendency of which is to move the former rearwardly or into open position. This tendency, however, is counteracted by a knuckle or bell crank 5 arm 70 provided for each slide and fulcrumed at 70' in a bracket 12⁵ projecting from the part 12⁴. These bell cranks are connected by wires or rods 71 to the main operating mechanism to be hereafter described.

By the adjustment of the wall 22' the measuring box 22 can be made to hold the exact quantity of the desired charge for a given set of molds T. Owing to the considerable large bottom opening 21' of the hopper 21 the cork mixture will be allowed to freely fall by its own weight into the box 22 when the upper slide 63 is withdrawn. A suitable agitator may be provided to stir 20 the mixture, if necessary. After the box is filled to its full capacity and the slide 63 closed, the lower slide 64 is slowly opened to allow the mixture to flow in a uniform stream onto a steep chute 72 extending 25 downwardly toward the openings 12' of the cross bar 12. The slides 63, 64 are preferably so actuated relative to the plungers 20 that a part of the charge will already be deposited on the chute 72 adjacent to the openings 12' when the plungers during their upward stroke are just passing out from said openings 12', so that owing to the vacuum created at that moment in said openings the feeding of the charge will be greatly accelerated. The movement of the plungers is such, that for a short time they will remain at a standstill in their elevated position, in order to give the charge sufficient time to completely enter the tubes T.

40 As the plungers 20 during the operation of the machine have the tendency to vibrate there is danger that during their downward stroke they may miss passing into the openings 12' of the cross bar 12. To prevent this, I provide on the latter a suitable guide which prior to the plungers arriving at the openings will engage the same and guide them steadily into the openings 12'. Such guide may consist of an upstanding flange 50 73 rigidly fixed to the bar 12 and extending the entire length thereof or of that occupied by the series of openings 12' thereof. The flange is arranged opposite the chute 72 and has on its side facing the openings 12' 55 vertical semi-cylindrical grooves 73' to snugly engage the plungers 20. The flange also serves as a shield in that it prevents the cork mixture from dropping off the bar 12 while passing from the chute 72 into the opening 12' (Figs. 4 and 11).

60 On the shaft 53 is rotatively mounted a hollow shaft 74 constituting the main cam shaft of the machine. This shaft carries a ratchet wheel 75 having a single tooth. Fixed to the solid shaft 53 adjacent to said

ratchet wheel is a lever arm 76 carrying a pawl 77 (Figs. 3 and 4), which is adapted to cooperate with said ratchet wheel 75 to impart intermittent rotary motion to said hollow cam shaft 74. As the ratchet wheel 70 has only one tooth the engagement with the pawl will always take place at one and the same place. At the rear end of the table 10' I provide a large cam 78 which is adapted to make one revolution during a complete packing operation. This slow movement is effected through the medium of a worm gear 79 mounted on the horizontal spindle 80 carrying the cam 78. The worm 79 meshes with a worm spindle 81, extending parallel to shaft 74 and receiving motion through chain transmission 83 and sprockets 84, 85 from the main pulley shaft 82 arranged at the rear and below the table (Figs. 1, 3 and 6). From shaft 82 motion 85 is transmitted also to shaft 53 through sprocket chain 83^a and gears 84^a, 85^a (Fig. 3).

Provided below the table 10' is a train of gears 86, 87, 88, 89 driven through chain 90 sprockets 90, 91 and chain 92 continuously from the pulley shaft 82. This gear train drives a crank shaft 93. The crank arm 94 thereof is connected through a link 95 to a crank arm 96 fixed on a shaft 97 parallel to shaft 82 and carrying a spring actuated pawl 98 adapted to operate a ratchet wheel 99 mounted on the shaft 97. During one half of a revolution of the crank shaft 93, the pawl will be caused to feed the ratchet wheel 99. The shaft 97 of this ratchet wheel through gears 100, 101 will transmit movement to a crank shaft 102, the crank 103 of which is connected by a link 104 at 105 to a horizontally guided rack 106. This rack 105 meshes with a pinion 107 fixed on the lower end of the spindle 14 which carries the turntable 15, 16 on which the two sets of tubes or molds T are mounted (Fig. 6). During the packing period the pawl 98 is held out 110 of contact with the ratchet 99. This I accomplish by the following mechanism:

In a bracket 108 fixed to and projecting downwardly from the lower face of the table 10' at 109 is pivoted an arm 110 extending 115 across the ratchet 99 and from the free end of which projects upwardly through the table 10' a push rod 111. The arm 110 is actuated by a spring 112 so as to normally be raised and thereby engage and lift the 120 pawl 98 from the ratchet 99. Fulcrumed on the upper face of the table 10' near the push rod 111 is a bell crank 113 one arm of which is adapted to act on the push rod 111 and the other is connected by a link 114 to a 125 lever 115 fulcrumed on the table at 116 and carrying a roller 117 adapted to be actuated once during a complete packing operation by the large cam 78.

At the moment when the last of the series 130

of compression strokes during a packing operation has been effected the cam 78 causes the lever 115 to swing forwardly and thereby operate the bell crank 113 so as to depress the push rod 111, as a result of which the arm 110 is depressed releasing the pawl 98 so as to permit it to engage the ratchet 99 and transmit rotation thereto. The rotation of the ratchet 99 will cause the rack 106 to move longitudinally and rotate the pinion 107 thereby turning the turntable 15, 16 around the axis of the spindle 14 and reversing the position of the two sets of tubes T, i. e., bringing the rear packed set to the front and the front empty set into the packing position. On the release of the push rod 111 the arm 110 is drawn back into its elevated position lifting thereby the pawl 98 out of contact with the ratchet 99.

20 To properly guide the tubes T in the turntable or support 15, 16 I provide the following mechanisms:

Fixed centrally to the lower plate 15 is a member 118 which at each of its longitudinal edges is provided with a series of semi-circular notches 118' in number corresponding with those of the tubes T in one row and serving to engage the latter when positioned on the lower plate 15 (Figs. 4 and 13).
 25 From the upper plate 16 project downwardly two parallel rows of fingers 119 each formed with a lateral flange 119' (Figs. 2 and 4). These fingers serve to guide the tubes into the holes 16' of the plate 16 while they are being inserted from underneath the plate 16 in inclined position. The holes 16' are made somewhat larger than the outer diameter of the tubes and are formed with radial projections 16''. Extending 30 across each row of tubes and above the support 16 is a resilient member, such as spring wire 120 fixed in supports 121 and which is adapted when the tubes are passed into the holes 16' of the plate 16 to press them against the projections 16'' and thereby steady them in position (Figs. 4 and 12).

The lower plate 15 is advantageously supported on a flange 15' arranged on the table and in alignment with the rear series of tubes T so as to take up the thrust of the plungers during the compression strokes and thus act as a thrust bearing.

To obviate friction during the turning of the turntable 15, 16, after the completion of a packing operation, spindle 14 may be yieldingly supported in its bearings to allow the support 15 of being held somewhat raised from the flange or thrust bearing 15'. To this end the spindle 14 is borne with its lower end on a spring actuated pin 122 (Fig. 6).

The tubes must also be very exactly positioned relative to the plungers, since otherwise there is danger that the plungers while descending will be thrust against the upper edges of the tubes. To this end the upper

support 16 is provided at one or each end with a pin hole 123 (Fig. 12) into which is adapted to snap a vertically movable locking pin 124, (Figs. 1, 2 and 3). The latter is actuated by a spring 124' so as to be normally projected into the pin hole 123 and lock the support or turntable in position. When a packing operation has been completed it is necessary to have the turntable 15, 16 released to allow of its being turned 75 around the axis of the spindle 14. This unlocking is accomplished by the large cam 78 in the following manner:

The upper end of the locking pin 124 is pivotally connected to a crank arm 125 fixed to the front end of a horizontal spindle 126 rotatively borne in a stationary part of the frame. The rear end of said spindle carries another crank arm 127 which by a connecting rod 128 is connected to a crank arm 129 fixed to the front end of a horizontal spindle 130 extending immediately above and across the table 10' and rotatively borne in bearings 131. The rear end of said spindle 130 has fixed to it another crank arm 132 which through a link 133 is connected to a crank arm 134 on a shaft 135 supported in bearings 136. The rear end of said shaft 135 carries a roller arm 137 the roller 138 of which is actuated by the cam 78 once during a full revolution of the latter.

The valve chamber 139 of the pump 27 contains four valves 140 two for each cylinder. These valves through rods 141 are each controlled by a cam 142 fixed on the hollow cam shaft 74 (Fig. 3). When the pawl 77 is in engagement with the ratchet 75 motion is transmitted to the hollow shaft 74 whereby the four cams 142 will successively operate the valves 140 first those of one cylinder of the pump then those of the other. Thereby the balance beams 24 will be caused to lower the plunger beam 18 until the plungers 20 are thrust against the charge in the tubes T and subsequently raise the plunger beam 18 into initial position.

On the hollow shaft 74 are additional four cams 143 (Figs. 2, 3 and 4) of which each two are adapted through arms 144 fulcrumed at 145 and connected to the rods or wires 71 to successively actuate the bell crank 70 of each slide 63, 64 of the charge measuring box.

At the completion of a compression operation and after the plungers have left the tubes during their return stroke it is necessary to throw out of gear the hollow cam shaft 74 and to simultaneously throw into gear the mechanism operating the turntable or tube supports 15, 16. This last named operation, as has been explained, is effected through the push rod 111 by the large cam 78 (Fig. 6). The throwing out of gear of the hollow cam shaft 74 is accomplished in a similar manner by the large cam 78 120 125 130

through the medium of a rod 146 carrying a roller 147 adapted to be actuated by the cam 78 once during a complete packing operation. The forward end of said rod is 5 pivoted to a circular arm 148 fulcrumed at 149 to a stationary part 150 and adapted normally to lie below the circumference of the ratchet, but when raised through the medium of the rod 146 to lift the pawl 77 10 out of engagement with said ratchet 75, as a result of which the cam shaft 74 will dis- continue its rotation.

As the positioning and removal of individual molds or tubes onto and from the 15 turn table or support would entail some loss of time and because of the necessity of providing centering means for each individual tube, it may be advantageous to unite sets of tubes to a unit, i. e., provide sets of tubes 20 which at both ends are joined together to a rigid body, so that the tubes in positioning and removal may be handled all at once. Such modified construction is shown in Figs. 14 and 15. Here two sets of molds or 25 tubes T' are suitably fixed on top and bottom to cross pieces 151, 151' to form a unit. Such unit is adapted to be positioned between and securely supported by super- posed bars or supports 152, 152' centrally 30 mounted on the spindle 14. The lower bar 152 has at each end a short pin 153 which is adapted to snugly engage a hole 151^a provided at each end of the lower cross piece 151, while the upper bar 152' is pro- 35 vided at each end with a longer pin 154 adapted to engage a hole 151^b provided at each end of the upper cross piece 151'. While the lower bar 152 may be perma- 40 nently fixed in position on the spindle 14 the upper bar 152' may be made adjustable vertically on said spindle 14 to permit the unit to be easily and quickly positioned in or removed from the packing position. The upper bar 152' may be slotted or perforated 45 (not shown) to permit the passage of the plungers therethrough while reciprocating vertically.

The mode of operation is as follows:—

Two sets of tubes to be packed are placed 50 by the operator in upright position on the turntable 15, 16. The two sets are to be packed successively. The set to be first packed is located on the rear side of the turntable, while the other set is on the front 55 side thereof. Both, the plunger beam 18 and the compressor 32 are in their elevated positions, with the gripper members 39 ex- tending as shown in Fig. 8 clearing the path 60 of the beam 18. The locking pins 124 by their springs 124' hold the turntable 15, 16 steady in packing position. The cork mix- ture is then allowed to flow into and fill the hopper 21 from a suitable source.

When the machine is started the measur- 65 ing device is first operated, the two cams

143 actuating the stops 70 of the upper slide 63 of the measuring box 22 permitting said slide to open under the action of the springs 69, as a result of which the box is filled to the full capacity with the desired charge. 70 Upon the return of the stops 70 into initial position the slide 63 is closed. Simultaneously with the closing of slide 63 the stops 70 of the bottom slide 64 are actuated by the corresponding cams, releasing said 75 slide 64 so that it will now open under the action of its springs 69 and permit the contents of the box 22 to drop onto the chute 72. Then by the return of the stops 70 into initial position the slide 64 will be closed. 80 About that time the pump 27 is operated by the opening of the inlet valve 140 of one of the cylinders through the action of the corresponding cam 142 on the cam shaft 74. As a result thereof the beam 18 begins its 85 first downward stroke. The beam descends until its plungers 20 passing through the openings 12' into the tubes T strike against the charge. The beam 18 will then stop for an instant, the pressure exerted by the pump 90 being overcome by the resistance offered by the charge. When the beam 18 reaches the lowest point of the stroke under the action of the pump 27 the compressors 32 begin their downward stroke and the pawls 38 95 which have been engaging the short ratchets 35 pass onto the elongated ratchets 36. The compressors 32 become thereby released and through the action of the spring actuated pinions 40 are instantly turned around 45° 100 as a result of which one set of the grippers 39 on each compressor are thrown into the path of the catches 18' of the beam 18.

In relation to the beam 18 or the catches 18' thereof the grippers of the compressors 105 32 are so arranged that when the beam reaches its lowest position during the action of the pump there will be a gripper on each compressor just about even with the upper face of the corresponding catches 18'. The 110 downward movement of the compressors 32 is now positively continued by said grippers. This part of the downward stroke constitutes the actual compression stroke, whereby the charge is compressed to the de- 115 sired density.

Prior to the completion of the return stroke of the plunger beam 18 the compressors 32 begin their ascent whereby the pawls 38 which have been engaging the upper 120 ratchets 36 holding grippers 39 projecting toward the beam will now pass back onto the ratchets 35 releasing the compressors 32 and thus permitting them to be turned back into inoperative position through the action 125 of the spring actuated pinions 40. Now the balanced beams 24 are operated in the re- verse direction by the other pump cylinder whose valves 140 are now successively actuated by the corresponding cams 142 where- 130

by the plunger beam 18 is raised to its initial or elevated position.

This completes one phase or cycle of a complete packing process.

5 Prior to the next stroke of the plungers 20 the slides 63, 64 of the measuring box are operated in the manner heretofore described to deposit a new charge of the same quantity onto the chute 72. Then the plunger beam 18 is operated in the same manner under the action of the pump until the plungers are thrust against the new charge. 10 This time the plungers under the action of the pump will have a shorter stroke, i. e., 15 a stroke lessened by the compressed column in the tubes, say $1\frac{1}{3}$ " according to our example. Thereupon the compressors 32 will start their downward movement and become first released to swing with a new set of 20 grippers 39 into the path of the catches 18', of which the lowest ones are now flush with and engage the latter effecting the compression of the second charge to the same degree as during the first cycle.

25 After the return of the compressors 32 and of the beam 18 into initial position the second phase or cycle is completed.

These phases are repeated with standard size tubes T and with charges each about 5" 30 column, about eighteen times. At the end of the last phase the cam 78 which during the entire period makes only one revolution throws out of gear the hollow cam shaft 74 by lifting the pawl 77 out of engagement 35 with the ratchet 75 through the arm 148 so that the operation of the cams 142 actuating the valves 140 of the pump 27 and of the cams 143 actuating the slides 63, 64 ceases. Simultaneously the rod 114 is acted 40 upon by the same cam 78 effecting the depression of the arm 110 with the consequent release of the pawl 98 so that the latter is allowed to engage the ratchet 99 transmitting movement therethrough to the shaft 97. 45 From the latter longitudinal movement is imparted to rack 106 through the gears 100 and 101 and crank 103, transmitting thereby rotary motion to the pinion 107 on the spindle 14 of the turntable 15, 16 and reversing the position of the two sets of tubes T in relation to the packing position. Of course prior to the release of the pawl 98 the pin or pins 124 are lifted from the upper plate 16 of the turntable through the action 55 of the main cam 78 on the roller lever 137 in the aforescribed manner.

While I have described the different details of the machine, I do not wish to limit myself to the same, since the construction 60 of the machine may be variously modified without departing from the spirit of my invention.

What I claim is:—

1. In a machine of the character described, 65 a plunger adapted to enter a stationary

chamber containing material to be compressed, and two independently propelled means, one to permit the said plunger to move at variable and the other at constant strokes within said chamber to compress successive charges therein to a predetermined density. 70

2. In a machine of the character described, a plunger adapted to enter a chamber containing material to be compressed, and 75 plunger actuating means permitting said plunger to move at variable strokes within said chamber to compress successive charges to a predetermined density, said means including a combination of yielding and positive means. 80

3. In a machine of the character described, a plunger adapted to enter a chamber containing material to be compressed, yielding means permitting said plunger to move at variable strokes within said chamber according to the preceding filling therein and positive means for causing equal extent of movement of said plunger in said chamber to compress successive charges to predetermined density. 90

4. In a machine of the character described, the combination with a stationary chamber receiving successive charges of material, a plunger adapted to enter said chamber to compress the successive charges therein and two independently propelled means, one permitting said plunger to move at variable strokes and the other causing the same to move at constant strokes within said chamber to compress said charges to predetermined density. 95

5. In a machine of the character described, the combination with a chamber to contain material to be compressed, of a plunger adapted to enter said chamber to compress successive charges of said material, two independently propelled means, one permitting said plunger to move at variable strokes and the other causing the same to move at constant strokes within said chamber and means for holding said chamber stationary during the entire packing operation. 100

6. In a machine of the character described, a plunger adapted to enter a chamber to compress material therein, the extent of the successive entries of said plunger being determined by the preceding filling in said chamber and means for causing said plunger to move an additional extent in said chamber uniform during all compression strokes to compress the successive charges to a predetermined density. 115

7. In a machine of the character described, a plunger adapted to enter a chamber to compress material therein, means carrying said plunger, resilient means permitting said first named means to successively move at different extent according to the preceding filling in said chamber, and positive means 120 125 130

- to additionally move said first named means, at each successive stroke thereof, a uniform extent, to compress the successive charges to the predetermined density.
5. 8. In a machine of the character described, a plunger adapted to enter a chamber to compress material therein, counterbalanced means carrying said plunger, resilient means permitting said first named means to successively move at different extent according to the preceding filling in said chamber, and positive means to additionally move said first named means, at each successive stroke thereof, a uniform extent, to compress the successive charges to the predetermined density.
10. 9. In a machine of the character described, a counterbalanced plunger adapted to enter a chamber to compress material therein, resilient means permitting said plunger to move at different extent according to the preceding filling in said chamber and positive means for additionally moving said plunger in said chamber to compress the preceding charge to the predetermined density.
15. 10. In a machine of the character described, a counterbalanced plunger adapted to enter a chamber containing material to be compressed, pneumatic means to permit said plunger to move at different extent according to the filling contained in said chamber and positive means for additionally moving said plunger in said chamber to compress the preceding charge to the predetermined density.
20. 11. In a machine of the character described, an intermittently movable plunger adapted to enter a chamber to compress material therein, each compression stroke of said plunger being effected in two successive movements, resilient means for effecting the first of said movements to an extent varying according to the filling of said chamber and the second of said movements being constant for compressing each charge to a predetermined density.
25. 12. In a machine of the character described, a plunger adapted to enter a chamber to compress material therein, resilient means to impart successively varying movements to said plunger according to the extent of filling of said chamber, and positive means to compress each successive charge to the same predetermined density, said positive means including reciprocating lugs.
30. 13. In a machine of the character described, a plunger adapted to enter a chamber to compress material therein, resilient means to impart successively varying movements to said plunger according to the extent of filling of said chamber, and positive means to compress each successive charge to the same predetermined density, said
- positive means including reciprocating adjustable lugs.
35. 14. In a machine of the character described, a plunger adapted to enter a chamber to compress material therein, pneumatic means for imparting successive intermittent movements to said plunger according to the filling contained in said chamber and positive means to impart additional movements to said plunger to compress each charge to the same predetermined extent, said positive means including reciprocating lugs.
40. 15. In a machine of the character described, a plunger adapted to enter a chamber to compress material therein, mechanically controlled means to feed successive charges into said chamber, resilient means to move said plunger in said chamber subsequent to each operation of the feeding means, the extent of such movement being determined by the preceding filling in said chamber and means to additionally move said plunger in said chamber at a constant stroke to compress each successive charge to the predetermined density.
45. 16. In a machine of the character described, a chamber to contain material to be compressed therein and adapted to be held stationary during the packing operation, a plunger adapted to enter said chamber, means to feed successive charges into said chamber, means to move said plunger into said chamber subsequent to each operation of the feeding means, the extent of such movement varying with the filling in said chamber, means to additionally move said plunger in said chamber at constant strokes, to compress each successive charge to the predetermined density, and means for moving said chamber out of filling position after the completion of the entire packing operation.
50. 17. In a machine of the character described, a reciprocatory beam, a plunger carried by said beam and adapted to successively enter a chamber to compress material therein, a compressor consisting of a longitudinally movable and rotary body formed with lugs displaced longitudinally and at an angle relative to one another and adapted to successively engage said plunger beam, means for temporarily holding said compressor with its lugs clearing the path of the plunger beam, and means for intermittently turning said compressor to successively bring the lugs in juxtaposition to said plunger beam.
55. 18. In a machine of the character described, a reciprocatory beam, a plunger carried by said beam and adapted to successively enter a chamber to compress material therein, a compressor consisting of a longitudinally movable and rotary body having a

- plurality of lugs displaced at an angle relative to one another and longitudinally of the body and adapted to successively engage said beam, a spring actuated means to intermittently rotate said body to successively bring the lugs into juxtaposition to said plunger and means to temporarily hold said body against rotation and in a position in which said lugs will clear the path of said beam.
19. In combination with a reciprocating member of progressively changeable stroke, of positive means to move said member, said means comprising a longitudinally movable and rotary body having a plurality of longitudinally displaced lugs arranged at an angle to one another and adapted to successively engage said member, means for intermittently revolving said body to successively bring the lugs in juxtaposition to said member and means for temporarily holding said body from turning and in a position in which said lugs will clear the path of said member.
20. In a machine of the character described, a counter-balanced plunger adapted to enter a chamber to compress material therein, pneumatic means permitting said plunger to reciprocate at strokes varying with the filling of said chamber, positive means for moving said plunger in said chamber to compress the material to a predetermined density, means for supplying said chamber with successive charges of predetermined quantity and means for displacing the chamber from its filling position after the same has been completely packed.
21. In a machine of the character described, the combination with a movable body, of a compressor consisting of a longitudinally movable and rotary member and means projecting from the circumference of said member and adapted at times to engage said member and depress the same.
22. In a machine of the character described, a compressor as per claim 21, whose members are arranged in a plurality of sets displaced radially relative to one another.
23. In a machine of the character described, a compressor as per claim 21, and means for intermittently rotating said compressor to successively bring the different sets into operative position.
24. In a machine of the character described, the combination with a compressor as per claim 21, of means for controlling the rotary movement of said compressor.
25. In a machine of the character described, a longitudinally movable and rotary compressor having radially displaced sets of members, two ratchets on said compressor formed in extension of one another, the teeth of said ratchets being arranged at an angle to one another, and a stationary pawl adapted when the compressor is moved longitudinally to alternately engage said ratchets and while passing from one onto the other to release the compressor and permit it to make a turn, to bring a set of said members into or remove the preceding set of members from operative position.
26. In a machine of the character described, the combination with a compressor as per claim 25, of spring actuated means to impart rotary motion thereto.
27. In a machine of the character described, the combination with a compressor as per claim 22, of means for imparting thereto longitudinally reciprocating movement and means for intermittently rotating it around its longitudinal axis.
28. In a machine of the character described, a vertically reciprocating plunger beam, counterbalanced means operatively connected to said beam, and cam controlled pneumatic means for moving said counterbalanced means.
29. In a machine of the character described, a plunger beam, and operating means therefor including a constantly driven shaft, a hollow cam shaft thereon, and cam controlled coupling means interposed between said two shafts.
30. In a machine of the character described, a plunger beam and operating means therefor, including a constantly driven shaft, a hollow cam shaft thereon, a one tooth ratchet carried by the latter, a pawl carried by said first named shaft and adapted to normally cooperate with said ratchet and cam controlled means for lifting said pawl from said ratchet at the completion of the packing operation.
